LAMP HOUSING FOR A PHOTOGRAPHIC ENLARGER

Danuse Mazurova, Prerov, Czechoslovakia, assignor to Meopta, Narodni Podnik, Prerov, Czechoslovakia

Filed Jan. 9, 1969, Ser. No. 15,267

Claims priority, application Czechoslovakia July 10, 1968

Term of patent 7 years

Int. Cl. D16—05

U.S. Cl. D61—1

FIG. 1

FIG. 1 is a side elevational view of the lamp housing embodying my new design.

FIGS. 2 and 3 are top and bottom plan views, respectively.

I claim:

The ornamental design for a lamp housing for a photographic enlarger, as shown.
